FLY SWATTER

Filed March 20, 1930

Inventor:
CLYDE T. KIRKBY.
By James, Addington,
Ames & Frable, Attys.

UNITED STATES PATENT OFFICE

CLYDE T. KIRKBY, OF CHICAGO, ILLINOIS

FLY SWATTER

Application filed March 20, 1930. Serial No. 437,295.

This invention relates to a fly swatter and has special reference to a toy gun provided with a swatting member adapted to be forcibly projected to kill a fly or other insect when properly aimed.

More particularly, this invention relates to a fly swatter comprising a swatting disk secured to a resilient supporting member on the end of a plunger, the plunger being guided in a housing in the form of a gun or rifle and being actuated to the release of a trigger by a rubber band or other like means extending substantially parallel with said plunger and adjacent thereto.

The device of this invention is primarily to afford considerable amusement to children and at the same time to achieve a useful result in an effort to exterminate flies and other insects. It is known that the force with which the swatting disk is projected, although sufficient to kill a fly, will not mar the furniture nor break delicate objects on which flies may light. The rapidity with which the article of this invention operates will not permit the escape of the insect by frightening before the disk is close thereto as is the case when an ordinary fly swatter is swung through the air.

Applicant is aware of fly swatters of the same general characteristics as the one herein described, although in those prior art devices, the actuating means for the plunger is disposed axially thereof and interferes with the operation thereof as well as provides a rasping nose which is not desirable to the elders of the probable users. The device of this invention is believed to further improve upon the present known devices by reason of the plunger being positively guided in its reciprocal movement and, further, by reason of the plunger rod having a pad at its outer end to prevent the marring of furniture and the like. A helical resilient supporting member carrying a wire disk is mounted on the outer end of the plunger and is of a substantially smaller diameter than the diameter of the plunger. The plunger is given a necessary rigidity not essential to that great a degree in the helical supporting member.

One of the objects of this invention is to provide a device of the character noted above

in which the supporting member for the swatting disk is of a smaller or different diameter than that of the actuating plunger to which it is attached.

Another object of this invention is to provide a device as hereinbefore mentioned in which the actuating means for the plunger carrying the swatting disk extends substantially parallel with and adjacent to the plunger.

A still further object of this invention is to provide a device as recited above in which the plunger and actuating means therefor are housed in the casing, the latter being formed of a single piece of sheet material and having a guiding tube inserted therein for supporting the plunger.

Also, it is the object of this invention to provide a fly swatter which will be comparatively inexpensive to manufacture, simple in construction, and durable.

Other objects and advantages will herein after be more particularly pointed out and for a more complete understanding of the characteristic features of this invention reference may now be had to the following description when taken together with the accompanying drawings, in which latter:

Figure 1 is a vertical longitudinal sectional view of the device of this invention;

Fig. 2 is an elevational view of a fragmentary portion of the device shown in Figure 1 with the plunger thereof in an extended position;

Fig. 3 is a sectional view taken on the line 3—3 of Figure 1;

Fig. 4 is a sectional view taken on the line 4—4 of Figure 1;

Fig. 5 is a perspective view of the trigger of the device of this invention; and

Fig. 6 is a sectional view taken on the line 6—6 of Figure 1.

Referring now more particularly to the drawings, the device of this invention comprises a gun barrel 10 preferably formed in a single piece, as shown more particularly in the sectional view of Fig. 6, wherein a single sheet of tin or other metal is formed into a cross section of oblong-shape having flanges 11 bent back from the point of meeting on the

underneath side of the barrel, the flanges being engaged by a securing member 12 of a C-shaped cross section. After the elongated strip of material is formed into the barrel 10 and the lower edges thereof are formed in an abutting relation the securing strip 12, which is substantially the same length as the gun barrel, is inserted to encompass the flanges. The securing member 12 has a slidable engagement with the flanges and is moved forwardly into position after the forward end of the flanges 11 are threaded into one end of the securing member. In lieu of the above securing member, the edges 15 may join on the underneath side and be soldered in the usual manner.

The gun barrel 10 is secured to a handle portion 13, which latter may preferably be formed in two pieces clamped together by a pin 14 at the lower end thereof and a pin 15 at the upper end thereof, the pin 15 having the further function of providing a pivotal support for the trigger, as will hereinafter be more fully pointed out.

25 A guide tube 16 is disposed on the end of the gun barrel opposite to that end which is secured to the handle portion and provides a suitable support and guiding means for a plunger rod 17, the latter being of substantial diameter and having a slidable engagement in the guide tube. One end of the plunger rod 17 is provided with a U-shaped off-set portion 18, the extreme outer end 19 being formed at right angles to the axis of the 30 plunger rod and in the direction of the U-shaped portion 18 for engaging a lip 20 of a trigger 21.

Referring now more particularly to the illustration in Fig. 5 of the drawings in connection with Figure 1, the trigger 21 is preferably formed of a single strip of material comprising a body portion 22 having a finger piece 23 extending therefrom in a downward direction, the lip 20 being formed as an upwardly extending portion thereof and being bent substantially at right angles to the body portion and rearwardly thereof. The body portion is supported on ears 24 which are preferably likewise stamped of the same sheet 45 of material and bent at right angles to the body portion, the ears 24 having circular apertures 25 into which the pin 15 is journaled. The trigger is normally urged outwardly from the handle portion of the gun 50 by means of a spring 26 and is limited in the movement thereof by means of projections 24a striking against the handle, the spring being sufficiently stiff or strong to overcome the actuating means for the plunger 17.

60 The plunger 17 is reciprocally mounted in the gun barrel and guide tube, the plunger being manually urged within the gun barrel a sufficient distance to engage the end portion 19 with the lip 20 of the trigger 21. The actuating member, or, as shown in the draw-

ings, the elastic member or rubber band 27 forcibly projects the plunger 17 to a position forwardly of the gun barrel and guide tube at the release of the trigger. It is, of course, to be understood that various types of actuating means may be employed in lieu of the rubber band or elastic member 27, although for the purposes of this gun the means shown are preferable. The rubber band 27 is secured at one end thereof to the U-shaped portion 18 70 formed in the plunger 17 and at the other end to the hook-shaped portion 28 of a detachable end plug 29. The plunger 17 is limited in its forward movement by a removable pin or screw 30 disposed close to one end of the gun barrel. The U-shaped portion 18 of the plunger 17 strikes against this pin or screw 30 when it lifts the forward position after it is released by the trigger 21.

Should the elastic member, rubber band, or other actuating means 27 become broken or in any other manner inoperative, the gun is readily dismantled. For example, the pin or screw 30 may be removed together with the detachable end plug 29, whereby the guide tube and plunger may be readily lifted out of the barrel. After the actuating means is replaced between the hook of the end plug 29 and the U-shaped portion 18 of the plunger, the tube 16 is readily inserted into the end of the barrel 10, the pin 30 replaced and the end plug forced into engagement with the end of the barrel.

A helical resilient supporting member 31 is secured to the end of the plunger 17, the member having a conical outer contour, the apex end of the helical wire being wound around the end of the plunger and threaded through an aperture therein and the base end of the helical cone being secured to the outer periphery of a swatting disk 32. The swatting disk 32 is preferably formed of an annular disk of wire netting preferably bound by a cloth binding material 33. A small felt disk 34 is disposed at the end of the plunger 17 and is sewed or otherwise secured to the upper helices and acts as a buffer for the end of the plunger 17 when it is projected outwardly from the gun into the position shown in Fig. 2. It will be noted that the 100 diameter of the plunger 17 is substantially greater than the diameter of the wire forming the helical resilient supporting member 31. This is very desirable since it is not desired to mar the furniture or other objects on which flies light and, therefore, a very flexible swatting disk supporting member is desired. However, the plunger should be of substantial weight because of its operation and for the sake of durability. The felt pad 34 therefore prevents a misuse of the plunger 17.

While but a single embodiment of this invention is herein shown and described, it is to be understood that various modifications 120

thereof may be apparent to those skilled in the art without departing from the spirit and scope of this invention and, therefore, the same is to be limited only by the scope of the appended claims and the prior art.

I claim:

1. A device of the character described comprising a barrel housing, a plunger longitudinally reciprocal in said housing and comprising a rod having an offset portion on the inner end thereof for arresting the movement in one direction, actuating means lying adjacent said rod and extending between and connected to said offset portion and the outer end of said housing, a trigger for engaging said plunger, a resilient supporting member comprising a helical wire of substantially less diameter than that of said plunger on the outer end thereof, and a swatting disk on said supporting member, said disk being forcibly projected by said actuating means at the release of said trigger.

2. A device of the character described comprising a barrel housing, a plunger longitudinally reciprocal in said housing and comprising a rod having an offset portion on the inner end thereof for arresting the movement in one direction and an end portion adjacent said offset portion at substantially right angles to the axis of said rod, actuating means lying adjacent said rod and extending between and connected to said offset portion and the outer end of said housing, a trigger for engaging said end portion of said plunger, a resilient supporting member on the outer end of said plunger, and a swatting disk on said supporting member, said disk being forcibly projected by said actuating means at the release of said trigger.

3. A device of the character described comprising a barrel housing, a plunger longitudinally reciprocal in said housing and comprising a rod having an integrally formed U-shaped offset portion on the inner end thereof and an end portion adjacent said offset portion at substantially right angles to the axis of said rod, an elastic member lying adjacent said rod and extending between and connected to said offset portion and the outer end of said housing, a trigger for engaging said end portion of said plunger, a resilient supporting member on the outer end of said plunger, and a swatting disk on said supporting member, said disk being forcibly projected by said actuating means at the release of said trigger.

4. A device of the character described comprising a barrel housing, a guide tube in one end of said housing, a plunger longitudinally reciprocal in said guide tube and said housing, actuating means adjacent said plunger and extending substantially parallel therewith, a trigger for engaging said plunger, a resilient supporting member on the outer end of said plunger, and a swatting disk on said

supporting member, said disk being forcibly projected by said actuating means at the release of said trigger.

5. A device of the character described comprising a barrel housing, a removable plug for one end of said housing, a plunger longitudinally reciprocal in said housing, actuating means lying adjacent said plunger and extending between and connected to one end of said plunger and said removable plug, a trigger for engaging said plunger, a resilient supporting member on the outer end of said plunger, and a swatting disk on said supporting member, said disk being forcibly projected by said actuating means at the release of said trigger.

6. A device of the character described comprising a barrel housing formed into an oblong cross-section of a single sheet of material, a removable plug for one end of said housing, a guide tube disposed in the upper portion of said housing extending longitudinally thereof, a plunger reciprocally mounted in said guide tube and said housing, actuating means for said plunger, a resilient supporting member on the outer end of said plunger, and a swatting disk on said supporting member, said disk being forcibly projected by said actuating means.

In witness whereof, I have hereunto subscribed my name.
